CIGARETTE PACKAGE

Bruce McPherson, Greenville, S. C., assignor of
one-half to Thomas W. Edwards, Greenville,
S. C.

Application March 28, 1934, Serial No. 717,839

11 Claims. (Cl. 206—48)

This invention relates to containers for cigarette packages or cigarettes and the object of the invention is to provide a novel container formed of a single blank of material adapted to be folded about a cigarette package with one portion of said blank serving to hold the container in folded condition and at the same time serve as a cover for matches appropriately secured on the container, the invention being a further development of my prior Patent No. 1,944,098, issued January 16, 1934.

Referring to the accompanying drawing, which is made a part hereof and on which similar reference characters indicate similar parts,

Figure 1 is a plan view of the blank from which the container is formed,

Figure 2 is a perspective view of the folded container,

Figure 3 is a section on line 3—3 of Figure 2,

Figure 4 is a perspective view of a modified form of the container, and

Figure 5 is a plan view of a portion of a modified form of the invention.

In the drawing reference character 10 indicates one portion of the blank formed of any suitable material divided by a plurality of parallel crease lines 11 and 12 defining the back 13, the sides 14 and the front flaps 15 of the container. One of the flaps 15 is reduced in width and extends to form a relatively long flap 16 provided with crease lines 17. The sides of the flap 16 are notched at the points 18 and are cut back at the points 19 to form the tabs 19 for a purpose which will later be described. The other flap 15 is provided with a slot 20 formed therein of a length equal to the width of the flap 16 and positioned parallel but spaced from the crease line 12 to receive the end of the flap 16.

The back 13 extends to form the other portion 21 of the container which is divided by a plurality of crease lines 22 and 23 defining the bottom 24, the front 25, the top 26 and a retaining tab 27. The edges 28 and 29 of the front 25 are cut back in the manner clearly shown in the drawing. The upper end of right side of the portion 21 is cut back as indicated at 30, so that the top 26 and the tab 27 are substantially equal to one-half the width of an enclosed package of cigarettes to permit easy withdrawal of the cigarettes. The back 13 is provided with a slot 31 of a length equal to the width of the tab 27 to receive the tab 27 to maintain the package in the container. The front 25 is provided with a slot 32 positioned centrally thereof so that when the container is folded the slot is parallel to the slot 20 to also receive the

end of the flap 16. The bottom 24 is provided with an opening 33 formed therein to permit the end of the package of cigarettes to be seen in order to readily determine the brand enclosed in the container.

A match card 33 is secured by a staple 34 or in any other suitable manner along the crease line 12 with the match heads extending in the same direction as the free end of the flap 16. A striking surface 35 of any suitable material is secured beneath the staple on the match card and when the container is folded the free end of the flap 16 is tucked under this striking surface as in the conventional type match folder.

In the modified form shown in Figure 4, a slot 36 may be provided parallel to the match card adjacent the crease line 12 to receive the free end of the flap 16. The striking surface 37 in this case may be fixed in any suitable manner to the side, as shown, or at any other appropriate point desired.

In the form shown in Figure 5, the flap 16 may be dispensed with and a conventional match folder 40 may be secured by means on a staple 41 to the front flap 15 with the free end extending outwardly in the same manner as the flap shown in Figure 1.

The container above described is folded as follows:

The portion 21 is folded along the crease lines 30, 22 and 23, thus defining one edge of the back 13, the bottom 24, the front 25, the top 26 and the tab 27. The left side of the portion 10 is folded along the crease lines 11 and 12 forming one edge of the back and the side 14, with the free end of the flap 16 or the free end of the match folder 40 as in Figure 5, extending through the slot 32. The right side of the portion 10 is likewise folded along the crease lines 11 and 12 with the end of the flap 16 or the free end of the match folder 40 threaded through the slot 20, with the front flap 15 of this side extending under the match card 33. The edge of this front flap extends under the tabs 19 to hold it firmly in place, and the flap 16 is then tucked under the striking surface 35. The notches 18 formed in the sides of the flap 16 engage the ends of the slot 20 to further lock the container in fixed position.

The package of cigarettes is then placed in the container and the tab 27 is forced in the slot 31 to complete the assembly.

In the case of the form shown in Figure 4, the tab 16 is inserted in the slot 36 rather than under the striking surfaces as in the preferred form shown in Figure 2.

The container thus formed protects the cigarettes against crushing and serves not only as a cigarette container but as a container for sufficient quantity of matches necessary to ignite the 5 cigarettes enclosed therein. The structure is such that a portion of the container serves to lock the container in folded condition and a cover for the matches appropriately secured thereon.

The surface of the container may be used for 10 advertising purposes and the like. The container may be cheaply and readily produced since it consists of a blank form of appropriate material with a match folder or a match card and striking surface fixed thereon as above specified. 15 The device is of novel construction not only from the standpoint of usefulness but is of considerable commercial value.

It will be obvious to those skilled in the art 20 without departing from the spirit of the invention and therefore I do not limit myself to what is shown in the drawing and described in the specification, but only as indicated by the appended claims.

25 Having thus fully described my said invention, what I claim as new and desire to secure by Letters Patent, is:

1. A container for a package of cigarettes comprising a blank, the ends of one portion constructed to be folded inwardly to form the sides and front flaps of said container, one of said front flaps being reduced and extending to form a relatively long flap and the other portion of said blank constructed to be folded to form the bottom, front, top and securing tab of said container, said front and other of said front flaps being provided with slots therein to receive the end of the long flap to maintain said container in fixed position, said long flap being constructed to cover 40 a match card fixed on said container.

2. A container for a package of cigarettes comprising a blank, the ends of one portion being constructed to be folded inwardly to form the sides, front flaps and locking flap of said container, and the other portion constructed to be folded to form the bottom, front, top and securing tab of said container, said front and one of said front flaps being provided with slots therein to receive the free end of said locking flap to hold 50 said container in folded condition, said flap serving to cover a match card fixed on said container.

3. The combination of a container and a match card appropriately fixed thereon comprising a back, sides and overlapping front flaps, one of said front flaps being provided with a slot therein and the other with an elongated locking flap, said locking flap being constructed to be threaded through said slot to lock the container in fixed position with the projecting end thereof 55 constructed to engage and cover said match card.

4. A container for a package of cigarettes comprising a blank provided with a series of crease lines, one portion of said blank being constructed to be folded to form the back, sides, front flaps 65 and locking flap of the container and the other portion of said blank being constructed to be folded to form the bottom, front, top and securing flap of said container, said front and one of said front flaps being provided with slots therein to receive the end of said locking flap to hold 70 said container in fixed position with the free

end of said flap constructed to engage and cover a match card fixed on said container.

5. The combination of a container and a match card comprising a back, sides and overlapping front flaps, one of said flaps being provided with a slot therein and the other being reduced to form a locking flap, said locking flap constructed to be inserted beneath said slotted front flap, through said slot to hold the container in fixed position with the free end of said locking flap constructed to engage and cover said match card. 10

6. The combination of a container and a match card comprising a back, sides and overlapping front flaps, said flaps being provided with parallel slots formed therein, one of said flaps being 15 further provided with a locking extension formed thereon constructed to be threaded through the slot in other of said front flaps to hold the container in fixed position with the free end covering said match card and engageable in the other 20 of said slots.

7. The combination of a container and a match card fixed thereon comprising a back, sides and overlapping flaps, one of said flaps being provided with a slot therein and the other with an 25 elongated locking flap, said locking flap constructed to be threaded through said slot to lock said container in fixed position with the free end covering said match card, and means for maintaining the free end of said flap in position. 30

8. A container for a package of cigarettes comprising a back, sides and overlapping front flaps, one of said flaps being provided with a slot therein and the other with a locking tab formed on its edge adapted to be inserted in said slot to hold 35 said container in fixed position, and a card provided with an overlapping edge fixed to said container adapted to be covered by said tab with the free end of said tab secured beneath the overlapping edge. 40

9. A container for a package of cigarettes comprising a back, sides and overlapping front flaps, one of said flaps being slotted and the other being provided with a tab formed on its edge adapted to be threaded through said slotted flap to hold 45 said container in fixed position, a card fixed to the surface of one flap extending over the other flap constructed to be covered by said tab, and means for maintaining the end of said tab in fixed position after being bent over said card. 50

10. The combination of a container for a package of cigarettes and a match card attached to the container, said container comprising a back, sides and overlapping front flaps, one of said front flaps being slotted and the other being provided with a projecting tab secured thereto 55 constructed to be threaded through said slotted flap to hold said container in fixed position and to cover said match card.

11. The combination of a container for a package of cigarettes and a match card attached to the container, said container comprising a back, sides and overlapping front flaps, one of said front flaps being slotted and the other being provided with a projecting tab secured thereto 65 constructed to be threaded through said slotted flap to hold said container in fixed position and to cover said match card, and means for maintaining the free end of the tab in position. 70
